LESLIE R. PRIEST, OF OAKLAND, CALIFORNIA.

GAS-ENGINE PISTON.

1,254,353.

Specification of Letters Patent. Patented Jan. 22, 1918.

Application filed February 8, 1917. Serial No. 147,312.

To all whom it may concern:

Be it known that I, LESLIE R. PRIEST, a citizen of the United States, residing at Oakland, in the county of Alameda and State of California, have invented certain new and useful Improvements in Gas-Engine Pistons, of which the following is a specification.

My invention relates to a piston of the trunk type, particularly adapted for use in internal combustion engines.

In such engines, as is well known, in order to minimize the vibration caused by the movements of the reciprocating parts, namely the pistons and connecting rods, and, therefore, to obtain the maximum efficiency from the engine, it is highly desirable to make such parts as light as is consistent with the requisite amount of strength. Heretofore pistons have been made almost universally of cast iron, for the reason that this material not only has sufficient hardness to prevent excessive wear, but also expands and contracts, with changes of temperature, at approximately the same rate as the cylinder wall, thus preserving, under all conditions, a proper running fit between piston and cylinder.

Cast iron pistons are necessarily heavy, however, and therefore cast aluminum has come into limited use. Now aluminum has the disadvantages, first of having a much greater coefficient of expansion than iron, so that an aluminum piston must be a comparatively loose fit in an iron cylinder; and second, aluminum, when raised to the working temperature of a gas engine piston, wears very rapidly. Therefore, aluminum pistons must not only be loose at first, but this looseness rapidly increases as the engine is used. The serious disadvantages of a loose fitting piston are too well known to require further elaboration.

The object of the present invention is to provide a piston, of the trunk type, which is light; which has approximately the same amount of expansion and contraction as the cylinder in which it operates; and which has sufficient resistance to wear to insure a long life. A further object is to provide an improved means for supporting the wrist pin within the piston, so that the body or skirt of the piston is not distorted by the strains occasioned by the pressure upon said pin.

It is to be understood that the invention is herewith illustrated and hereinafter de-

scribed in its preferred form, but that changes may be made in form and construction, within the scope of the claims hereto appended, without departing from the spirit 60 of the invention. With this in view, the invention is fully described with reference to the accompanying drawings, wherein—

Figure 1 is a part sectional elevation of my improved piston. 65

Fig. 2 is a part sectional elevation taken at right angles to Fig. 1.

Fig. 3 is a part sectional plan, taken on the line 3—3 of Fig. 1, the lines 1—1 and 2—2 indicating respectively the planes of 70 Figs. 1 and 2.

Fig. 4 is a sectional elevation of a portion of a modified form of my piston.

Referring more particularly to the drawings, the reference numeral 1 designates the 75 piston head, which is preferably cast of aluminum or an alloy thereof, for the sake of lightness. This head has a rim 2 of sufficient width to accommodate packing rings 3, here shown to the number of two. At 80 this portion, the rim 2 is made of a diameter to provide as close a fit as possible in the cylinder, allowing for the different amounts of expansion between the piston and the cylinder. 85

Below the packing ring portion 2 is a portion 4 of reduced diameter, formed upon its exterior surface with a screw thread, as shown at 5. The skirt of the piston is formed preferably of a seamless cylinder 6 90 of steel or similar material, reinforced at its upper end by an interior ring 7, the latter being permanently secured to said skirt 6 throughout its entire circumference, as by welding or brazing, and formed interiorly 95 with a screw thread adapted to coact with the thread 5 upon the piston head flange 4. The end of the skirt 6 is lineally slotted, as at 8, said slots extending transversely through the ring 7. These slots are provided for the purpose of allowing the head and the skirt to have unequal expansion, without loosening the joint. In addition to the screw threads 5, the skirt 6 is held upon the head 1 by a series of rivets 9, one between each pair of adjacent slots 8, and passing through the skirt, the ring 7, and the head flange 4.

The piston pin, not shown in the drawings, is carried by bosses 10 projecting downwardly from the head 1, and preferably cast integrally therewith. Thus the piston pin is

entirely within the skirt 6, being placed therein through a hole 6" in said skirt; and the thrust of the pin is carried directly to the head 1, and any distortion caused thereby cannot affect the skirt 6.

5 The skirt 6, of course, forms the guide for the piston, and takes the entire wear caused by its travel within the cylinder. Said skirt, being made of iron or steel, can 10 be made a close fit within the cylinder, without danger of binding when hot. The upper end of said skirt, where it is slotted and fastened to the head flange 4, is contracted sufficiently to allow for the greater expansion 15 of the aluminum head, but this difference in diameter, being necessarily small, does not appear in the drawings. Moreover, by making the head of aluminum or an alloy thereof, and the skirt of steel, as 20 shown in Figs. 1, 2 and 3, a very light piston is obtained, which possesses all the advantages of an iron piston in regard to strength and wearing qualities.

The skirt may be made of cast iron, as 25 shown at 6' in Fig. 4. In this case the reinforcing ring is eliminated, the upper end of the skirt being made thicker, as at 7', and screwed directly onto the head flange 4, as at 5'. Said skirt is slotted at its upper end, 30 as indicated by the dotted line 8', and is additionally secured to the head flange 4 by rivets 9', in a manner identical with that described above. The cast iron skirt provides 35 a cheaper, though slightly heavier construction than the steel skirt.

I claim:—

1. A piston comprising a head portion of relatively light metal; an independent skirt portion of a relatively hard, wear-resisting metal having a coefficient of expansion different from that of the head portion metal; and means joining said portions adapted to permit their unequal expansion.

2. A piston comprising a head portion of relatively light metal, such as aluminum; an independent skirt portion of a relatively hard, wear-resisting metal, such as iron; and means joining said portions adapted to permit their unequal expansion.

50 3. A piston comprising a head member of relatively light metal, formed with a journal boss extending inwardly therefrom; an independent skirt portion of a relatively hard, wear resisting metal having a coefficient of expansion different from that of the head portion metal, said skirt portion sur-

rounding and partially inclosing said boss in spaced relation; and means joining said portions adapted to permit their unequal expansion.

60 4. A piston comprising a head portion formed of aluminum, a cylindrical skirt portion formed of iron and having a series of slots extending downwardly from its upper end, and means for securing the slotted end 65 of said skirt to said head.

5. A piston comprising a head portion provided with annular circumferential grooves; packing rings positioned within said grooves; a cylindrical flange of less diameter than 70 said grooved portion and extending downwardly therefrom; a pair of spaced journal bosses extending downwardly from said flange; a skirt portion, of substantially the same diameter as the grooved portion of said 75 head, adapted to surround said bosses in spaced relation and to fit over said flange; said skirt being provided with a series of spaced lineally disposed slots extending downwardly from its upper end; inter-engaging screw threads formed upon the exterior of said flange and the interior of the slotted end of said skirt; and means for additionally securing said skirt upon said flange.

80 6. A piston comprising a head portion, a cylindrical skirt portion associated therewith, said skirt portion being formed upon one end with a plurality of longitudinally directed tongues, and means for independently securing each of said tongues to said head, to permit said skirt and said head to have unequal expansion and contraction.

85 7. A piston comprising a head portion formed of a relatively light metal such as 95 aluminum; a cylindrical skirt portion associated therewith, said skirt portion being formed of a relatively hard, wear-resisting metal such as iron and provided upon one end with a plurality of longitudinally directed tongues; and means for independently securing each of said tongues to said head to permit said skirt and said head to have unequal expansion and contraction.

100 In testimony whereof I have signed my 105 name to this specification in the presence of two subscribing witnesses.

LESLIE R. PRIEST.
